UNITED STATES PATENT OFFICE.

ROBERT OSKAR KRASSELT, OF LEIPZIG, GERMANY.

WASHING BASIN.

Application filed March 4, 1927, Serial No. 172,789, and in Germany October 6, 1926.

The washing arrangements placed at the disposal of the public in public-rooms, principally those in railway-stations, require for hygienic reasons special attendance, whereby expenses are caused which are covered by a moderate charge to be paid by the person who uses the washing arrangement. It has been proposed to provide in connection with the washing utensils, a penny-in-the-slot machine or to cash the fees by the attendant. In the latter case it happens frequently that a portion of the receipts is embezzled by the attendant.

In order to prevent this and to make it impossible that the washing utensils be used without paying a fee, the washing basin rotatable around an eccentric axis is combined, according to the invention, with a counting mechanism and held in the emptying-position and in the position of use by an automatically acting locking device, which can be unlocked only by means of a special key. The novelty consists in providing notches in a disk fixed on the axle of the washing-basin and a lock with snap-latch which is designed to automatically engage with one of these notches. The spring-controlled latch may be connected with the locking-bolt of the locks by means of an intermediate lever.

Two embodiments of the invention are shown, by way of example, in the accompanying drawing in which:—

Fig. 1 shows in side elevation the washing table and the washing basin the latter being shown in full lines in the position of use and in dash-lines in the vertical position.

Fig. 2 is a top plan view of Fig. 1.

Fig. 3 is an end elevation.

Figs. 4-6 show similar views to Figs. 1 to 3, the locking mechanism being of other construction.

The washing basin *a* is oscillatably mounted in the table plate *d* by eccentric journals *b*. On one of these journals *b* a disk *g* is fixed, which has notches *i*, *i'*, designed to receive a spring-controller latch *k*. The latch *k*, which forms at the same time the locking bolt for the lock *m*, can be pulled back only by means of a separate key which is in possession of the attendant. The counting mechanism can be arranged so that it is

operated either when the basin oscillates to adopt the vertical position or when it is being lowered into the position of use. In the drawing the counting mechanism is shown operated at the lowering of the basin *a*. A nose *n* at the front end of the basin *a* bears, at the descending of the basin *a*, upon a feed-lever *o* of the counting mechanism *p* and depresses the same, in compressing a spring, so that it makes the counting mechanism *p* advance one unit. As the basin *a* is locked in the lower position by the snap-latch *k* engaging with the notch *i'* it cannot be emptied without assistance of the attendant, so that emptying can be done only by the attendant, when the basin is being cleaned. The lock *m* which, in the form of construction shown in Figs. 1 and 2, is embedded in the top surface of the table plate *d* may be arranged, as shown in Figs. 4 to 6, in the front portion of the table plate-frame, i. e. at a point which is not liable to get dirty. In this case the snap-latch *k* is connected to the locking-bolt *k* of the lock *m* by a two-armed pivoted lever *r*.

I claim:

1. Tippable washing-basin for public use, comprising in combination with a basin proper oscillatably mounted in a table plate by eccentric journals, a counting mechanism, means for operating said counting mechanism from the oscillating basin, and means for locking the basin in the position of use and in the emptying position said means to be unlocked with the aid of a special key.

2. Tippable washing-basin for public use, comprising in combination with a basin proper oscillatably mounted in a table plate by eccentric journals, a counting mechanism, means for operating said counting mechanism from the oscillating basin, a disk having two notches and fixed on one of said journals, a lock in the table plate, and a locking-bolt in said lock serving as snap-latch engaging with the one or other of said notches and locking the basin in the position of use and in the emptying position said snap-latch to be unlocked with the aid of a special key.

3. Tippable washing-basin for public use, comprising in combination with a basin

proper oscillatably mounted in a table plate by eccentric journals, a counting mechanism, means for operating said counting mechanism from the oscillating basin, a disk having two notches and fixed on one of said journals, a spring-controlled snap latch for locking said basin in the position of use and

in the emptying position, a lock to be operated by a special key, and a two armed pivoted lever connecting said locking bolt 10 with said snap-lock.

In testimony whereof I affix my signature.

ROBERT OSKAR KRASSELT.
